(57) **CLAIM**

We claim the ornamental design of a pintle latch, as described and shown.

DESCRIPTION

FIG. 1 is a perspective view of a pintle latch showing our new design;

FIG. 2 is a side elevational view of the pintle latch, with the opposite side view being a mirror image thereof;

FIG. 3 is a front elevational view of the pintle latch;

FIG. 4 is a rear elevational view of the pintle latch;

FIG. 5 is a top plan view of the pintle latch; and,

FIG. 6 is a bottom plan view of the pintle latch.

The broken lines are for illustrative purpose only and form no part of the claimed design.
